UNITED STATES PATENT OFFICE.

JOHN A. LARSON, OF HAYFIELD, MINNESOTA.

DESIGN FOR A DISPLAY-RACK.

No. 39,209.

Specification for Design.

Patented March 17, 1908.

Application filed January 3, 1908. Serial No. 409,246. Term of patent 7 years.

To all whom it may concern:

Be it known that I, JOHN A. LARSON, a citizen of the United States, residing at Hayfield, in the county of Dodge and State of Minnesota, have invented a new, original, and ornamental Design for Display-Racks, of which the following is a specification, reference being had to the accompanying drawing, forming a part thereof.

The figure is an elevational view in per-

spective of a display rack, illustrating my new design.

I claim:

The ornamental design for a display rack, as shown.

JOHN A. LARSON.
